SANDAL

Alexander L. Srajer, Oak Park, Ill.

Application November 20, 1939, Serial No. 305,361

1 Claim. (Cl. 36—11.5)

The invention relates to footwear and more especially to sandals.

The primary object of the invention is the provision of an article of this character wherein the sole area is divided transversely so as to have a toe portion hinged at the dividing area and thereby providing flexibility of the sandal when being worn to assure comfort, the hinging of the toe portion being of novel construction.

Another object of the invention is the provision of an article of this character wherein the sole, toe and heel as well as the arch area are made from fibrous material, such as wood, and this wooden body is divided transversely along the sole area to permit flexing of the toe portion, the hinge connecting the toe portion being made from a leather or flexible strap divided along the longer edges thereof for effecting an overlap with respect to the fasteners securing the said strap in place and in this way concealing the fasteners and avoiding injury therefrom when wearing the sandal.

A further object of the invention is the provision of an article of this character, which is simple in its construction, thoroughly reliable and efficient for comfortable wearing, neat in appearance, durable and inexpensive to manufacture.

With these and other objects in view, the invention consists in the features of construction, combination and arrangement of parts as will be hereinafter more fully described in detail, illustrated in the accompanying drawing, which discloses the preferred embodiment of the invention and pointed out in the claim hereunto appended.

In the accompanying drawing:

Figure 1 is a perspective view of a sandal constructed in accordance with the invention.

Figure 2 is a bottom plan view thereof.

Figure 3 is a sectional view taken on the line 3—3 of Figure 2 looking in the direction of the arrows.

Figure 4 is a sectional view on the line 4—4 of Figure 2 looking in the direction of the arrows.

Figure 5 is a fragmentary perspective view of the hinging member for the sandal.

Similar reference characters indicate corresponding parts throughout the several views in the drawing.

Referring to the drawing in detail wherein a practical embodiment of the invention is illustrated, a sandal embodying the present invention is indicated generally at A and includes a heel end 10, a sole area 11 and a toe end 12, respec-

tively. The toe end 12 is separated from the sole area 11 in that a slit 13 transversely of the sole area and toe end creates the dividing line therebetween so that the toe end 12 and the sole area are susceptible of movements relative to each other. It is preferable to have the heel end 10, sole area 11 and toe end 12 constructed from fibrous material, preferably wood. The upper face of the sandal A is properly concaved, as at 14 and 15, respectively, for conforming to the bottom surface of a foot of a wearer for assuring comfort and maintaining proper tread in the wearing of the sandal.

Interposed between the heel end 10 and the toe end 12 in the under face of the sandal A is an arch 16 creating an instep portion 17, this being conventional.

Next to the slit 13 transversely of the sandal A in the upper face of the sole area 11 and the toe end 12 is countersunk a hinge member preferably an elongated flexible strap 18 made from leather, although it may be made from any other suitable material. This strap 18 at its longer edges is slotted inwardly through the free longitudinal edges thereof to provide base attaching flanges 19 and overlapping flanges 20, respectively. The flanges 19 have passed therethrough suitable fasteners 21, which secure the strap to the sole area 11 and the toe end 12 for hinging the latter in place while the overlapping flanges 20 are disposed over the heads 22 of the fasteners 21 concealing these and protecting a foot of the wearer of the sandal from injury which might be inflicted in the wearing of the sandal if the fasteners were exposed and susceptible of contact with the bottom of the foot during the wearing of such sandal.

The flanges 20 overlie the fasteners 21 and the outer faces of these flanges are substantially flush with the upper surfaces of the sole area 11 and the toe end 12, being effective as cushions or pads so that no injury can result from the fasteners 21 making contact with the bottom of the foot of the wearer.

Engaged transversely through suitable passages provided in the sole area 11 and toe end 12 is a tie lacing or cord 23, which is adapted for the fastening of the toe end of the sandal to the foot of the wearer. The heel end 10 has provided transversely therein a suitable passage or bore for a terminally looped lacing or cord 24, the terminal loops being indicated at 25 and have trained therethrough a heel lacing or cord 26 so as to hold the latter about the ankle of the foot of the wearer to avoid the release of the heel

end 10 of the sandal from the foot when such sandal is being worn. The ends of each of the lacings or cords 23 and 26 are tied to each other for the holding of the sandal upon the foot of a wearer and during the wearing of the latter.

What is claimed is:

In a sandal, comprising a sole of rigid material formed of a toe section and a separate heel section having straight walls abutting, a pliable

strip countersunk into the upper faces of the sections adjacent the abutting edges and having splits on its edges forming double flaps at each edge, means passing through the lower flaps into 5 the toe and heel sections and the upper flaps covering said securing means and said flaps having their upper faces in a plane with the upper faces of the toe and heel sections.

ALEXANDER L. SRAJER.
